[57] CLAIM

The ornamental design for a case for a portable computer game or similar device, substantially as shown and described.

DESCRIPTION

FIG. 1 is a top plan view of a case for a portable computer game showing our new design;

FIG. 2 is a side elevation view, taken from the right side of the case as viewed in FIG. 1;

FIG. 3 is a front elevation view of the case;

FIG. 4 is a bottom plan view of the case;

FIG. 5 is a side elevation view, taken from the left side of the case as viewed in FIG. 1; and

FIG. 6 is a rear elevation view of the case.
